METHOD AND APPARATUS FOR PRODUCING
PRINTING PLATES

Lawrence G. Taylor, Miami, Okla.

Application March 3, 1933, Serial No. 659,561

11 Claims. (Cl. 41—25)

My invention relates to a method and apparatus for producing printing plates, and has for its main object to prepare a form or design in relief and cast thereon a stereotype plate of a character to be employed in reproducing the design by the usual printing process.

Another object is to produce a relieve form or design matrix that is responsive to the heat of the casting, or to heat applied thereto before casting, 10 to increase the thickness and density of the matrix.

Another object is to provide a suitable coating material which is applied to a base to form a desired design, which design is thereafter coated 15 over with a masque material of such nature that, when washed with a suitable solvent, the latter can be removed at those portions in contact with the design. The masque material is also of such nature that it will expand when in contact with 20 the hot stereotype metal forming the plate that is cast thereon, or by the application of heat before the stereotype is cast.

Other objects will become apparent from a study of the detailed specification which follows, 25 taken with the accompanying drawing, wherein—

Figure 1 is a plan view of an applied design;

Figure 2 shows a cross section on line 2—2 of Fig. 1.

30 Figure 3 is a view in cross section showing a coated design;

Figure 4 is a view in cross section showing a stereotype cast onto a formed matrix; and

Figure 5 shows a plan view of a stereotype plate.

35 According to the present methods employed in printing, of which I am aware, the usual practice is to prepare printing forms by the process of photo-engraving. This process is not only expensive, but also requires an excessive amount 40 of time to effect the various steps necessary for that process. Furthermore, the art of photo-engraving requires the employment of skilled workmen and more or less complicated apparatus.

45 According to my method and apparatus, a stereotype may be produced in a minimum of time and at a very small cost as compared with the present methods. My process is particularly suited to the needs of a small newspaper plant which is not equipped to produce printing plates of the photo-engraved type and its use by such plants affords a much desired saving in the time and expense which results from the present dependence upon a specially equipped central engraving plant.

50 My method contemplates the forming upon a

suitable matrix surface of a design to be printed. I employ a novel and specially prepared material or coating in the form of a solution and apply the material to the surface in a manner to produce the design in relief. The design is made exactly as the printed proof from the finished stereotype is to appear. When the design is completed, it is permitted to dry, or heat is applied thereto to facilitate drying and a second specially prepared coating is brushed on immediately over the original design and in and around it. The latter coating is prepared from a novel combination of ingredients and is of such nature that it will be caused to expand upon the application of heat and for a specific purpose. The coated design is then dried and additional coats are similarly applied according to the needs of the particular design. The matrix surface, including the design and the masque coating, are then washed with a solution that will loosen the upper coating at portions adjacent to the design portions in a manner to remove portions of the upper coating and the material forming the design, thereby leaving the design configuration in and between the upper coating. Thereafter, the matrix is dried thoroughly by heating and the molten type metal is cast directly upon the finished design which causes the remaining coating to expand to make a deep depression in the stereotype, leaving the design in bold relief thereon. The coating material may likewise be expanded sufficiently by heat before casting to form a satisfactory printing plate when cast.

55 Referring to the drawing, a desired design 1 is applied to a surface 2 by coating thereon a quantity of what may be called my A-mixture, a preferred composition of this solution being 35 85% of powdered resin and 15% powdered albumin dissolved in sufficient gasoline or benzol to cause the mixture to flow freely when applied by a brush or pen. Any desired color may be imparted to this mixture by adding a dye or printing ink. The use of powdered albumin is not necessary and a satisfactory composition is made with the resin alone dissolved as set out. The addition of albumin improves the mixture. When the design is finished, it is permitted to dry naturally, or sufficient heat is applied to cause the mixture to crystallize, more or less, and dry out. Other resin solvents such as carbon disulphide may be used.

60 I now apply to the design a coating of what may be termed a B-mixture, a preferred composition of which comprises powdered albumin 5%, dextrin 80% and bicarbonate of soda 15%, dis-

solved in water to form a semi-paste. This B-mixture is brushed on immediately over the original design and around it to form a flat surface. A mixture of these substances is adapted to assume a hard and crystalline form when given the wash described later and to expand upon the application of heat. One or more coats of this B-mixture are applied to the design and each coat must be dried, preferably by heating, before the next application. This B-mixture acts as a masking material and permits a ready removal of the design by use of a special washing solution. For coatings of the nature described, a preferred and practical wash liquid, I have found by experiments to be gasoline, the action of which serves, in some manner, to loosen the A-mixture which constitutes the design, and harden the B-mixture. The gasoline is preferably flowed onto both the coated side and rear side of the cardboard base. When the gasoline has evaporated to some extent, the design is heated carefully but not sufficiently to expand the coating of B-mixture. The first wash and the application of heat ordinarily causes the design to loosen, but a repetition of this procedure may be necessary. The design is further washed or brushed out by means of cotton saturated in gasoline. Other suitable wash liquids are benzol, carbon disulphide and turpentine. The application of heat is not necessary in the washing process except to hasten the procedure. Equally good results may be obtained by submerging the matrix material in the wash solution and permitting it to remain therein until the design cleans out easily. On the drawing, numeral 3 indicates the B-mixture coating.

The final step in my novel process comprises the step of casting the stereotype. The washed out and dried matrix is placed in a usual form of casting box 4, and a quantity of molten casting metal 5 is poured over the matrix. This metal flows into the depressed or washed out portions which extend through the coating 3 to the level upper surface of the base 2. The heat from the molten metal will cause the B-mixture coating 3 to expand in a manner to thicken this coating whereby to accentuate the molded design impression and increase its relief.

The cast stereotype 5 forms an exact replica of the design 1, but reversed end for end whereby it may be mounted in a printing press, inked and employed in the usual manner for impressions. If desired, the base member 2 may be made from transparent material which may be placed over a design to be reproduced and the latter may be traced by applying my A-mixture.

In a modified form of my method, I propose to apply a uniform layer of my B-mixture directly upon a base surface. After the same is dry, or partially so, a desired design may be etched directly through or on this layer. This layer of transparent B-mixture may be applied to a transparent base 2, and any design which is to be reproduced can be placed under this base and the design may be engraved through or on this layer. In either case, a stereotype plate may be cast directly upon this etched layer. The heat from the molten metal will cause the layer to thicken to permit a pronounced relief of the design on the finished plate. If desired, the etched coating may be expanded by heat applied prior to the casting step. The coating may likewise be expanded before the etching is done since the coating surface is more pliable after being fully expanded by heat.

While I have stated preferred proportions for the ingredients of both the A and B mixtures disclosed, it is to be understood that these proportions may be varied within reasonable limits without materially affecting the practical results of my process and such variations are intended to be embraced within the scope of the claims which follow.

What I claim is:

1. The method of making a printing form which comprises applying material to a plain surface to form a design, applying a coating to completely cover said design, treating said coating and design with a solvent to remove the design and the coating in contact therewith thereby providing a matrix, and casting a stereotype directly on said matrix. 10

2. In a method as set forth in claim 1, wherein the coating applied to the design is formed from material adapted to expand with heat. 20

3. The method of making a printing form which comprises applying material to a plain surface to form a design, coating the design with a mixture containing dextrin, albumin and bicarbonate of soda, treating said coating and design with a solvent to remove the design and the coating in contact therewith, thereby providing a matrix, and casting a stereotype plate directly on said matrix. 25

4. The method of making a printing form which comprises tracing a design with a mixture of resin, albumin and a solvent, applying a coating to completely cover said design, treating said coating and design with a solvent to remove the design and the coating in contact therewith thereby providing a matrix, and casting a stereotype plate directly on said matrix. 30

5. The method of making a printing form which comprises tracing a design with a mixture of resin and a solvent, applying a coating to completely cover said design, treating said coating and design with a solvent to remove the design and the coating in contact therewith thereby providing a matrix, and casting a stereotype plate directly on said matrix. 40

6. In a method as set forth in claim 4, wherein the coating comprises albumin, dextrin and bicarbonate of soda, the heat from the stereotype metal adapted to expand said coating to increase the relief of said design on the plate. 50

7. In a method as set forth in claim 1, wherein the plain surface is transparent to permit tracing thereon a design appearing from its undersurface.

8. The method of making a matrix which comprises coating a surface with a mixture of dextrin, albumin and bicarbonate of soda, engraving a design upon said coating, and applying heat to said coating to increase its thickness and provide full relief of said design. 55

9. The method of making a matrix which comprises coating a surface with a mixture of albumin, dextrin and bicarbonate of soda, heating to increase the thickness of the engraving surface and to make said surface more pliable, and engraving a design upon said surface. 60

10. The method as set forth in claim 8 wherein the heat is provided by casting a stereotype plate directly on the engraved coating.

11. A composite matrix board for use in forming designs to be printed, comprising a transparent base material and a transparent coating applied thereto, said coating containing dextrin, albumin and bicarbonate of soda. 70
